UNITED STATES PATENT OFFICE.

WILLIAM BARTHOLOMEW AND CHARLES M. LEARY, OF CHICAGO, ILLINOIS, ASSIGNORS
TO TROY LAUNDRY MACHINERY COMPANY, LTD., OF CHICAGO, ILLINOIS, A CORPO-
RATION OF NEW YORK.

STARCH-TABLE.

1,211,385.

Specification of Letters Patent.

Patented Jan. 9, 1917.

Application filed April 18, 1913. Serial No. 762,069.

To all whom it may concern:

Be it known that we, WILLIAM BARTHOLOMEW and CHARLES M. LEARY, citizens of the United States, residing at Chicago, in the county of Cook and State of Illinois, have invented certain new and useful Improvements in Starch-Tables, of which the following is a specification.

Our invention relates in general to laundry apparatus, and more particularly to a table for facilitating the starching of articles, and especially portions of garments, such, for instance, as the attached cuffs of shirts.

In order to efficiently apply starch to laundered articles the starch should be maintained at a substantially constant predetermined temperature, so as to have the proper consistency to uniformly saturate the articles dipped therein. Heretofore, in starching articles by hand, it has been customary to heat the starch in a receptacle placed on a stove until it assumes the desired consistency, and to then remove the receptacle from the stove and dip the articles in the starch. As the starch necessarily gradually cools, this practice requires the frequent return of the receptacle to the stove, which interrupts the work of starching.

The primary object of our invention is to provide a starching table having therein a receptacle for containing the starch, and a jacket surrounding the receptacle, through which a heating medium circulates to constantly maintain the starch at the temperature necessary to keep it in the proper fluid condition.

A further object of our invention is to provide a starching table having therein a starch-containing receptacle surrounded by a heating jacket, the table being also provided with a ridge above the surface thereof around the receptacle therein, so as to prevent other portions of the garments on the table slipping into the receptacle than the portions which it is desired to starch.

Our invention will be more fully disclosed hereinafter with reference to the accompanying drawing, in which the same is illustrated as embodied in convenient and practical form, and in which—

Figure 1 is a vertical section; and Fig. 2 a plan view.

Similar reference characters are used to designate similar parts in the two figures 55 of the drawings.

Reference character A indicates a table, which may be supported in any convenient manner, as by means of legs a.

A' indicates a covering for the upper surface of the table, which is preferably made of sheet metal.

B designates a receptacle for containing the starch, such receptacle being located within an opening in the table, and preferably projecting a short distance above the upper surface thereof. The receptacle B is preferably divided into two or more compartments by means of one or more partitions, such as indicated at B'. It is desirable that different articles should be starched to different degrees, and hence by dividing the receptacle into compartments starch of different degrees of fluidity may be available, in which the different kinds of 75 articles may be dipped according to the degree of stiffness which it is desired to impart to the articles.

C designates a jacket surrounding the receptacle B and forming in conjunction 80 therewith a space around the side and bottom walls of the receptacle, to which a heating medium is supplied to maintain the starch contained in the receptacle at the temperature necessary to maintain the same 85 in the desired consistency. The upper edge of the jacket C projects above the top of the table and is curved inwardly and united to the upper edge of the surrounding wall of the receptacle.

D designates a conduit extending through the jacket C and secured thereto in any suitable manner to prevent leakage. A smaller conduit d extends within the space between the jacket and the bottom wall of 95 the receptacle and communicates with the inner end of the conduit D. The heating medium, such, for instance, as steam, is supplied through the conduit D from any suitable source, and is delivered from the inner 100 end of the small conduit d to the space between the jacket and receptacle.

E indicates an outlet conduit, which extends through the side wall of the jacket C and is secured thereto by suitable means to 105 prevent leakage. The outer end of the con-

duit E communicates with the interior of an overflow F, into which extends a vertical discharge conduit G. The upper end *g* of the discharge conduit G is located at a height desired for the level of the heating medium in the jacket C. A short cylinder H surrounds the upper end *g* of the discharge conduit G and is secured at its lower end within the upper end of the overflow F. 10 The cap K, having an outlet hole *k* for the escape of steam, is secured to the upper end of the cylinder H.

In order to permit the discharge of the starch from the receptacle B, a conduit depends downwardly from and communicates with each of the compartments of the receptacle. L' indicates one of such conduits depending from one of the compartments of the receptacle, and L² a similar conduit depending from a second compartment. Such conduits are made of copper and are soldered at their upper ends around the openings through which they extend in the bottom wall of a receptacle, as indicated at 25 *l'* and *l²*. The conduits L' and L² extend through holes in the bottom wall of the jacket C, and depending portions thereof are surrounded by exterior screw-threaded brass nipples M' M², which are suitably 30 united, as by means of solder, to the bottom wall of the jacket, as indicated at *m'* and *m²*. N' and N² indicate stop cocks secured to the lower ends of the brass nipples M' and M² for controlling the passage-ways through 35 the starch discharge conduits L' and L².

The operation and manner of using our improved starching table are as follows: Starch of the proper consistency is placed within the receptacle B, and when the receptacle is provided with compartments the starch supplied to the different compartments is of different degrees of fluidity. The heating medium, such, for instance, as steam, is supplied to the conduit D and is discharged from the inner end of the conduit d to the space between the jacket C and the side and bottom walls of the receptacle. The steam condenses so that the water of condensation fills such space and is kept at 40 the proper temperature by the continuous discharge of steam thereinto. When the water of condensation reaches the desired level within the jacket, it has also reached the level at the top *g* of the water discharge conduit G and then flows downwardly through such conduit. Any steam which may also pass through the conduit E to the interior of the overflow F rises through the short cylinder H and escapes through the 45 opening *k* of the cap K. When it is desired to remove the starch from the receptacle the stop cocks N' and N² are turned to open positions so as to permit the starch to flow downwardly from the several compartments 50 of the receptacle through the discharge con-

duits L' and L². The projection of the top of the receptacle above the surface of the table forms a ridge around the receptacle above the plane of the upper surface of the table, which prevents the slipping of the portions of the garments into the receptacle adjacent those portions which are to be starched and which are consequently allowed to depend over such ridge into the receptacle. For instance, when the cuffs attached to shirt sleeves are to be starched the shirt is laid upon the table with the cuffs depending within the receptacle. The portions of the sleeves adjacent the cuffs overlie the ridge around the receptacle, which tends to prevent the sleeve also slipping into the receptacle. 75 80

From the foregoing description, it will be observed that we have invented an improved starching table, the use of which facilitates the starching of articles, inasmuch as the starch is constantly maintained at the temperature necessary to produce the desired consistency, thereby avoiding the interruption in the operation of starching articles which is necessarily incident to the intermittent heating of the starch. It will be further observed that our invention permits the dipping of the portions of the articles which it is desired to starch without liability of the adjacent portions of the articles, which it is designed not to starch, slipping into the starch. 85 90 95

We claim:—

1. The combination with a table, of a starch containing receptacle located in an opening in the top of the table in a position to leave an adjacent part of the top of the table to form a supporting surface for portions of articles which are not to be starched, a jacket surrounding said receptacle, means for supplying a heating medium to the space between said jacket and receptacle, and an outlet conduit leading from the bottom of said receptacle for discharging the starch therefrom. 100 105 110

2. The combination with a table, of a starch containing receptacle located in an opening in the top of the table, a jacket surrounding said receptacle and permanently secured thereto as well as to the top of the table, a guard ridge surrounding the open top of the receptacle and projecting above the upper surface of the table for retaining the articles in position with portions depending into the receptacle and other portions resting upon the adjacent surface of the top of the table, and means for supplying a heating medium to the space between said jacket and receptacle. 115 120 125

3. The combination with a table, of a starch containing receptacle located in an opening in the top of the table, a jacket surrounding said receptacle and projecting through the opening in the table to which it 130

is secured, means for supplying a heating medium to the space between said jacket and receptacle, and means for automatically maintaining a predetermined level of the 5 heating medium in the jacket.

4. The combination with a table, of a starch containing receptacle located in an opening in the top of the table, a jacket surrounding said receptacle, an inlet conduit 10 for supplying steam to said jacket, an outlet conduit communicating with said jacket, an overflow casing with which said outlet conduit communicates, a water discharge pipe extending into said casing to the height 15 of the water lever desired in said jacket, and means for permitting the escape of steam from said overflow casing.

5. A table for the starching by hand of 20 laundried articles comprising a starch containing receptacle located in an opening in the top of the table, a jacket completely surrounding and secured to said receptacle and projecting through the opening in the table top, a partition in said receptacle 25 dividing the interior thereof into compartments, means for permitting the separate discharge of starch from each of said compartments, and means for supplying a heating medium to the space between said 30 jacket and receptacle.

6. In a device for facilitating the starching of laundried articles, the combination with a table, of a starch-containing receptacle located in an opening in the top of said 35 table and projecting above the upper surface thereof and secured thereto above the table top for retaining articles in position with portions depending into said receptacle and other portions resting upon the 40 adjacent surface of the table top, a jacket surrounding said receptacle, and means for supplying a heating medium to the space between said jacket and receptacle.

7. In a device for use in starching laundried articles, the combination with a receptacle for containing the starch, of a table 45 surrounding said receptacle upon which the articles to be starched are placed with portions thereof depending within said receptacle, a jacket surrounding the side and bot-

tom walls of said receptacle and permanently secured to the top thereof, means for supplying a heating medium to the space between said jacket and receptacle, and means for permitting the discharge of 55 starch from said receptacle.

8. In a table for the hand starching of articles, the combination of a plurality of starch-containing chambers depending below the top of the table and having their 60 upper edges projecting above the surface of the table to retain articles under treatment in position with portions thereof hanging downwardly within said chambers and with the remaining portions of the articles lying 65 on the adjacent surface of the table top, and a single jacket permanently secured to and completely surrounding said chambers for containing a heating medium to maintain the starch within said chamber in a pre- 70 determined consistency.

9. A table for the hand-starching of articles comprising a receptacle located in an opening in the top of and permanently secured to the table in a position to leave an 75 adjacent part of the top of the table to form a supporting surface for portions of articles which are not to be starched, the wall of said receptacle projecting above the upper surface of the table for retaining articles in position with portions thereof depending into the receptacle, a jacket surrounding said receptacle and secured thereto adjacent its top, a partition in said receptacle dividing the same into compartments, means for permitting the separate 80 discharge of starch from each of said compartments, and means for supplying a heating medium to the space between said jacket and receptacle for maintaining the starch 85 in said compartments at a predetermined 90 consistency.

In testimony whereof, we have subscribed our names.

WILLIAM BARTHOLOMEW.
CHARLES M. LEARY.
